Design

Edward Reynolds Hatrock. Des 1090

Patented March 29, 1859.

Dec. 1090

Edward Reynolds of Boston Mass.
Assignor to
Thomas W. Brown, of same place.
Letters Patent. No. 1090. Dated Mar. 3, 1857.

The schedule referred to in these Letters Patent and marking part of the same.

Dec. 1090

To all Persons to whom these Presents Shall come:

It is known that of Edward Reynolds of Boston, in the County of Suffolk, and State of Massachusetts, have invented or produced a new ornamental design for a Hat Rack; and I do hereby declare the same to be fully represented by the accompanying drawing, which exhibits a front elevation of it.

The design in question exhibits a basket of flowers suspended by a cord from a pin or knot, and having not only an elliptical mirror frame embraced by the cord but a series of wreaths of flowers and bands and tassels flanking the cords, and arranged in number, and with reference to the same as shown in the drawing.

At sundry parts of the arrangement, birds with curved tails are disposed to serve as hooks or means of supporting hats, when placed upon them.

The whole is to be of cast metal, or carved from some proper material, and when used is to be fastened to a wall.

In the drawings, *a*, is the basket; *b*, the mirror frame; *c, c*, the cords; *e, e*, the bands; and *f, f*, the tassels, while *g, g*, are the bird hooks and *h*, the collection of flowers.

I claim the new ornamental design of hat-rack as represented and described.

Witnesses,

R. H. Eddy

J. P. Hale, Jr.

350

Edward Reynolds.
